UNITED STATES PATENT OFFICE.

JOSEPH TAUSSIG, OF CHICAGO, ILLINOIS.

BRACKET.

1,283,964.

Specification of Letters Patent.

Patented Nov. 5, 1918.

Application filed February 28, 1918. Serial No. 219,570.

To all whom it may concern:

Be it known that I, JOSEPH TAUSSIG, a citizen of the United States, and a resident of Chicago, county of Cook, and State of Illinois, have invented certain new and useful Improvements in Brackets, of which the following is declared to be a full, clear, and exact description.

This invention relates to brackets and its 10 principal object is to provide a simple, cheap and practical bracket for supporting shelves and other articles. Another object is to provide a self alining bracket arranged for use on an upright supporting member, having 15 keyhole slots therein, for the reception of a bolt or screw, mounted in the bracket and acting to clamp the bracket upon the upright. Another object is to reduce the parts to a minimum and to reduce the number of 20 operators required to construct brackets of this type. With these and other objects and advantages in view, the invention consists in the several novel features hereinafter fully set forth and claimed.

25 The invention is clearly illustrated in the accompanying drawing in which:

Figure 1, is a side elevation of an upright supporting member and bracket containing a simple embodiment of the present invention; Fig. 2, is a longitudinal section taken on line 2—2 of Fig. 3; Fig. 3, is a rear view of the device; Fig. 4, is a horizontal section taken on line 4—4 of Fig. 2, and Fig. 5, is a horizontal section taken on line 5—5 of 35 Fig. 2.

Referring to said drawing the reference character 6, designates an upright supporting member, which for convenience may comprise the usual channel shaped bar 40 formed with key hole slots therein, one of which is shown at 7. The bracket 8, is preferably constructed of sheet metal, struck up by suitable dies, and comprises a horizontal shelf supporting arm 9, and an attaching 45 member 10, permanently secured to one end of the arm. The attaching member 10, is substantially T shaped in cross section and preferably comprises a sheet metal piece folded upon itself along the middle of its 50 length to provide a U shaped web 11, 11, and then bent at right angles to the web portion to form oppositely disposed, and alined base portions or flanges 12, 12. Openings 13, 13, are provided in the edge 14, of 55 the web portion into which project two

tongues 15, that are formed on one end of the arm 9. Preferably the tongues 15, fit snugly between the inner sides of the web pieces 11, and are spot welded thereto to permanently fasten the arm and attaching member together.

At a point between the tongues 15, the web pieces 11, are pressed outward to leave between them an opening through which passes a bolt or screw 16, the head 16^a, 65 of which is located on the rear side of the attaching member 4. A nut 17, is threaded on the bolt 16, and is adapted to bear against the adjacent edge of the attaching member. The bolt is prevented from turning in the 70 hole by a lug 18, which enters the key hole slot and strikes against the straight side thereof. The round portion 19, of the key hole slot is large enough to permit the passage of the bolt head therethrough and the 75 straight portion 20, is made narrower than the bolt head to provide bearing places for said bolt head, when the nut is screwed up against the attaching member.

The flanges or base portions are struck up 80 to form two oppositely placed tongues or lugs 21, which are bent back behind the rear faces of the flanges 12, and are arranged to engage the two sides of the round portions 19, of the key hole slot 7, when the 85 bracket is in place on the upright supporting member, and act to prevent tilting or turning of the bracket on said upright member. Said tongues or lugs 21, also act to correctly position the bracket on the upright 90 member by reason of their engagement with the side edges of the round portion of the keyhole slot.

To secure the bracket on the upright member, the nut 17, is unscrewed far enough 95 to permit the insertion of the bolt head through the round portion of the key hole slot. After the bolt head has been passed through the slot the bracket is lowered, thereby bringing the shank of the bolt into 100 the straight portion of the slot, and the two tongues 21, into the round portion thereof. The nut 17, is then tightened up against the front edge of the attaching member, thereby clamping it against the upright.

More or less variation of the exact details of construction is possible without departing from the spirit of this invention; I desire, therefore, not to limit myself to the exact form of the construction shown and de- 110

scribed, but intend in the following claims to point out all of the invention disclosed herein.

I claim as new, and desire to secure by 5 Letters Patent:

1. A bracket comprising an arm, an attaching member fixedly secured thereto, and having two oppositely disposed laterally projecting flanges adapted to bear against 10 an upright supporting member, each flange being formed with a struck up tongue extending back of the plane of the rear faces of said flanges, said tongues extending in opposite directions crosswise of the bracket 15 and being adapted to engage with and rest against side edges of the round portion of a key hole slot in the upright supporting member to determine the position of the bracket on said supporting member, a bolt 20 extending through said attaching member and straight portion of said key hole slot, and a nut threaded on said bolt.

2. The combination with an upright supporting member having a keyhole slot 25 formed therein, of a bracket having a pair of laterally projecting flanges arranged to bear against said upright supporting member, said flanges being formed with rearwardly depressed oppositely disposed 30 tongues seating in the round portion of the keyhole slot to determine the position of the bracket on said supporting member, and

clamping means between the upright supporting member and bracket having a portion passing through the straight portion of 35 said key hole slot.

3. A bracket comprising an arm and an attaching member permanently secured thereto at one end, and formed with two oppositely disposed lateral flanges adapted 40 to bear against a supporting member, each flange being formed with a rearwardly depressed laterally extending oppositely disposed tongue for engaging the side edges of the round portion of a keyhole slot of a 45 supporting member, to determine the position of the bracket on the supporting member.

4. A bracket comprising an arm formed at one end with two spaced tongues, an attaching member comprising a piece of sheet metal folded upon itself at the middle along a vertical line, said folding portion straddling the tongues of the arm and being spot welded thereto, said folded portions having laterally and oppositely bent flange portions, each formed with a rearwardly depressed tongue for positioning the bracket 50 on a supporting member, a clamp bolt extending through said attaching member between the tongues of the arm, and a clamp nut on said screw, substantially as and for 55 the purpose set forth.

JOSEPH TAUSSIG.
